UNITED STATES PATENT OFFICE

173,030

SHOE

John Hoza, Belcamp, Md., assignor to Bata Shoe Company, Inc., Belcamp, Md.

Application February 26, 1954, Serial No. 29,239

Term of patent 14 years

(Cl. D7—7)

To all whom it may concern:

Be it known that I, John Hoza, a citizen of the United States, residing at Belcamp, Maryland, have invented a new, original, and ornamental Design for a Shoe, of which the following is a specification, reference being had to the accompanying drawing, forming a part hereof.

I claim:

The ornamental design for a shoe, as shown.
